FISH LURE

Filed March 6, 1937

Inventor:
William G. Knapp
By Davis, Lindsey, Smith & Adams Atty's.

UNITED STATES PATENT OFFICE

105,113

DESIGN FOR A FISH LURE

William G. Knapp, Evanston, Ill.

Application March 6, 1937, Serial No. 68,053

Term of patent 14 years

To all whom it may concern:

Be it known that I, William G. Knapp, a citizen of the United States, residing at Evanston, in the county of Cook, State of Illinois, have invented a new, original, and ornamental Design for a Fish Lure, of which the following is a specification, reference being had to the accompanying drawing, forming a part thereof.

In the drawing the figure is a perspective view of a fish lure showing my new design.

I claim:

The ornamental design for a fish lure, as shown.

WILLIAM G. KNAPP.
